United States Patent Office

Des. 175,274
Patented Aug. 2, 1955

175,274

DESK CALENDAR OR THE LIKE

Jean O. Reinecke, Oak Park, Ill., assignor to U. O. Colson
Company, Paris, Ill., a corporation of Delaware

Application December 28, 1954, Serial No. 33,719

Term of patent 3½ years

(Cl. D74—5)

Fig. 2.

Fig. 3.

Fig. 4.

Fig. 1 is a perspective view of a desk calendar or the like showing my new design;

Fig. 2 is a front elevational view thereof;

Fig. 3 is an end elevational view thereof looking at the right hand end of Fig. 2; and

Fig. 4 is a top plan view thereof.

The dominant features of the design are shown in full lines.

I claim:

The ornamental design for a desk calendar or the like, as shown and described.
